Andrew Muir and Fred Cross, Saltcoats, Saskatchewan, Canada

Application June 26, 1933. Serial No. 677,745

6 Claims. (Cl. 120—32)

The present invention appertains to new and useful improvements in copy holders, such as can be employed in printing establishments and by typists in offices.

5 The principal object of the present invention is to provide a copy holder which can be operated in an easy and convenient manner.

Another important object of the invention is to provide a copy holder wherein the parts are 10 capable of being readily adjusted to meet various working conditions.

These and various other important objects and advantages of the invention will become apparent to the reader of the following specification.

15 In the drawings:—

Figure 1 represents a front elevational view of the machine.

Figure 2 represents a side elevational view of the device.

20 Figure 3 represents a side elevational view of the device, looking at the opposite side from that shown in Figure 2.

Figure 4 represents a vertical sectional view taken substantially on line 4—4 of Figure 1.

25 Figure 5 represents a fragmentary vertical sectional view taken substantially on line 5—5 of Figure 1.

Figure 6 represents a fragmentary side elevational view of the side of the machine shown in 30 Figure 3, with the roller supporting plate removed.

Figure 7 represents a cross sectional view through the roller shaft and disclosing the ratchet means.

35 Figure 8 represents a fragmentary vertical sectional view taken substantially on line 8—8 of Figure 4.

Figure 9 represents a fragmentary vertical sectional view taken substantially on line 9—9 of 40 Figure 1.

Figure 10 represents a perspective view of the adjustable pressure plate.

Referring to the drawings wherein like numerals designate like parts, it can be seen that a casing is provided which consists of the front wall 45 5 which is convex at its intermediate portion and slanting backwardly in the manner shown in Figures 2 and 3, while numerals 6 and 7 represent the side walls of this casing.

50 The front wall 5 is provided at its intermediate portion with a rectangular shaped opening 8 leaving marginal portions 9—9 at the opposite ends thereof and adjacent the side walls 6—7. Bridging this opening 8 is the pressure plate 10 which 55 has slots 11 at the ends thereof through which

the set screws 12 are disposed to thread through openings in the said marginal portions 9—9. The heads of the screws 9, when the screws are driven inwardly, will clamp against the plate 10 and secure the same with its upper edge in proper 60 spaced relation with respect to the upper edge of the opening 8, so that as much of the copy sheet 13 as desired may be made visible.

As is apparent in Figures 1 and 4, the copy sheet 13 is disposed into the opening 8 below the 65 pressure plate 10 and passes under the opening between the upper edge of the opening 8 and the upper edge of the pressure plate 10, and is fed by the rubber roller 14 which clamps the said copy sheet 15 against the inner side of the front 70 wall 5, adjacent the upper end thereof.

Cross members 16, between the side walls 6—7, support a pair of vertically disposed leaf springs 17 which engage against the shaft 18 of the roller 14 so as to force the roller in a direction clamping the said copy sheet 15 against the inner side 75 of the wall 5.

One end of the shaft 18, as shown in Figure 8, has a reduced portion 19 which extends through an elongated horizontally extending slot 20 in 80 the side 7 of the casing, while the other end of the shaft 18 extends through a rectangular shaped opening 21, as shown in Figure 6, and is supported by the removable plate 22 which partly closes the opening 21 when the same is secured 85 to the side wall 6 by the screw 23.

One end of the roller 14 is equipped with a ratchet wheel 24. A ring 25 is rotatably mounted on the shaft 18 and carries a pawl 26 engageable with the ratchet wheel 24. A rod 27 extends 90 from this ring 25 and connects to the intermediate portion of a lever 28 which has its pivot point at 29. A leaf spring 30, extending from a protuberance 31 on the side wall 7, bears against this lever 28 and maintains the same disposed upwardly against the stop strip 32, which stop strip is secured by a clamp screw 33 operating through a slot 34 in the front wall 5. The lever 28 operates through a slot in the front wall 5 and has a knob 35 at its outer end. 100

By referring to Figure 1, it can be seen that numeral 36 represents a collar secured to the outer side of each side wall 6—7 and each of these collars has a set screw 37 thereon whereby the aforementioned casing, consisting of the 105 walls 5, 6 and 7, can be adjustably supported upon the uprights 38. The uprights have bases 39 for attachment to a suitable supporting surface 40 and this supporting surface 40 has a base member 41 secured thereto and to this is swingably 110

connected an arm 42 having a knob 43 at its free end. A pivotal link 44 extends from the intermediate portion of the lever 42 to the outer knob end of the lever 28. It can be observed, that the lever 42 extends substantially beyond the outer end of the lever 28 and obviously, either of these levers can be operated for operating the roller 14 to feed the copy sheet.

By adjusting the stop plate 32, a greater or 10 less throw of the levers 28 and 42 can be obtained and this is desired when the lines of the copy sheet are double or triple spaced.

While the foregoing specification sets forth the invention in specific terms, it is to be understood 15 that numerous changes in the shape, size and materials may be resorted to without departing from the spirit and scope of the invention as claimed hereinafter.

Having described the invention, what is 20 claimed as new is:—

1. A copy holder comprising a casing having a front wall, said front wall having a sight opening therein behind which a copy sheet can move, a roller mounted behind the said front wall and 25 means for exerting pressure against the said roller to press a copy sheet against the inner side of the front wall in the region of the said sight opening.

2. A copy holder comprising a casing having a front wall, said front wall having a sight opening therein behind which a copy sheet can move, a roller mounted behind the said front wall, means for exerting pressure against the said roller to press a copy sheet against the inner side of the front wall in the region of the said sight opening, and means whereby the said roller 35 can be removed.

3. A copy holder comprising a casing having a

front wall, said front wall having a sight opening therein behind which a copy sheet can move, a roller mounted behind the said front wall, means for exerting pressure against the said roller to press a copy sheet against the inner side of the front wall in the region of the said sight opening, and means whereby the said roller can be rotated.

4. A copy holder comprising a casing having a front wall, said front wall having a sight opening therein behind which a copy sheet can move, a roller mounted behind the said front wall, means for exerting pressure against the said roller to press a copy sheet against the inner side of the front wall in the region of the said sight opening, and ball and ratchet means for driving the said roller.

5. A copy holder comprising a casing having a front wall, said front wall having a sight opening therein behind which a copy sheet can move, a roller mounted behind the said front wall, means for exerting pressure against the said roller to press a copy sheet against the inner side of the front wall in the region of the said sight opening, ball, ratchet and lever means for operating the said roller.

6. A copy holder comprising a casing having a front wall, said front wall having a sight opening therein behind which a copy sheet can move, a roller mounted behind the said front wall, means for exerting pressure against the said roller to press a copy sheet against the inner side of the front wall in the region of the said sight opening, ball, ratchet and lever means for operating the said roller, and an adjustable stop 110 for the said lever.
